F. A. L. CASSIDEY, OF NEWNANSVILLE, FLORIDA.

Letters Patent No. 64,650, dated May 14, 1867.

IMPROVEMENT IN COTTON-PRESS.

The Schedule referred to in these Letters Patent and making part of the same.

TO ALL WHOM IT MAY CONCERN:

Be it known that I, F. A. L. CASSIDEY, of Newnansville, in the county of Alachua, State of Florida, have invented a new and useful Improvement in Packer for Cotton and similar substances; and I do hereby declare that the following is a full, clear, and exact description thereof, which will enable others skilled in the art to make and use the same, reference being had to the accompanying drawings, forming a part of this specification, in which—

Figure 1 is a side view of my improved cotton-packer.

Figure 2 is a side view of the packing-cylinder.

Figure 3 is a vertical section of my improved packer taken through the line xx , fig. 1.

Figure 4 is a horizontal section of the packing-cylinder taken through the line yy , fig. 1.

Figure 5 is an under side view of the piston-head.

Figure 6 is the same view as fig. 5, showing the relative position of the packing-rods.

Similar letters of reference indicate like parts.

My invention has for its object to furnish an improved apparatus for packing cotton and other similar substances, and introducing them into bags or sacking; and it consists, first, in the construction of the slotted suspended packing-case or cylinder; in the combination with the cylinder of the ratchet-bars and springs, and of the piston-head; in the combination of the gear-wheels, shafts, pinion-wheels, and toothed bar with each other, with the piston-head, and with the frame of the machine; and in the combination of the hinged bottom with the packing-cylinder or case.

A is the frame of the machine, which consists of an upright frame supported upon a horizontal one, and strengthened with braces, as shown in figs. 1 and 3. B is the packing-cylinder or case, which is made in the form of a hollow cylinder, and is suspended at its upper end from the posts a' of the frame A, as shown in fig. 1. The cylinder or case B is slotted vertically from the upper end to near the lower end, as shown in the drawings. These slots are placed opposite each other, as shown in fig. 4, so that the rods C may project on each side of the cylinder or case B; as shown. The cylinder or case B is strengthened where weakened by the slots by straps b' , which are curved outward so as to allow the projecting ends of the bars or rods C to pass down within said straps, as shown in figure. H D are ratchet-bars attached to the sides of the cylinder B. At the sides of the slots in said cylinder, by slotted ears working on pins attached to the sides of the cylinder E, are springs attached to the side of the cylinder B, the ends of which press against the rear side of the ratchet-bars D forcing them forward over the slots so as to receive and hold the ends of the rods C, and yet be able to yield to allow the rods C to pass by the teeth of the bars. F is the bottom of the cylinder, which is secured at one side by the hinge G, and at the other side by the catch H, both hinge and catch being curved outward, as shown in fig. 3, so as to leave a space around the bottom of said cylinder for the reception of the bag or sacking, as shown in fig. 3. I is the piston-head, which fits into the cylinder B. The face of the piston I is grooved with one or more grooves in the line of the slots in the said cylinder B to receive the rods C, as shown in figs. 3 and 6. To the upper side of the piston-head I is attached the lower end of the toothed bar J, which passes up through guide holes in the horizontal bars a^2 and a^3 of the frame A. K is the crank-shaft, which revolves in bearings attached to the frame A, and has the crank L attached to one of its ends, and the fly-wheel M to the other. N is a small gear-wheel attached to the shaft K, the teeth of which mesh into the teeth of the gear-wheel O, attached to the end of the shaft P. The shaft P revolves in bearings attached to the frame, and carries a pinion-wheel, R, the teeth of which mesh into the teeth of the toothed bar J. The cylinder or case B has been described as being cylindrical in form, but it may be rectangular or square according to the form which it is desired the bales should have, the form being immaterial.

In using the packer, the apparatus is placed over a hatchway or other opening in the floor, the sacking is drawn over the bottom of the case B, and the bottom F of the said case closed down over it. The hoops or bands by which the bale is to be secured are then bent at their middle and passed down into the cylinder, and their projecting ends bent down over its upper edge so as to be out of the way. The case B is then filled by hand with loose cotton, the rods C are placed above it in the position shown in figs. 1, 3, 4, and 6, and forced down until the upper teeth of the racks D take hold of them. The piston I is then turned down, compressing

the cotton in the lower part of the case B. The piston is then run up, the racks D holding the rods C and the cotton down. The upper part of the cylinder B is again filled with loose cotton, another set of rods placed above it, and it is again forced down by the piston, when the lower set of rods may be withdrawn to be again used, and so on until the cylinder is full. The ends of the hoops are then bent down over the cotton and secured to each other in the ordinary manner, after which the rods C are all withdrawn, the bottom F opened, and the bale forced out of the cylinder B by the piston I drawing off with it the sacking. In situations where it is not convenient to have an opening in the floor for the completed bale to pass through, the posts a' of the frame A may be jointed just below the point at which the cylinder B is supported, so that when the bale is completed the upper part of the frame and the cylinder may be inclined and the bale be forced out upon the floor upon which the machine stands.

I claim as new, and desire to secure by Letters Patent—

1. The suspended slotted packing-case or cylinder B or equivalent, in combination with the frame A, substantially as herein shown and described.
2. The combination of the ratchet-bars D, springs E, and rods C, with the packing-case B, substantially as herein shown and described.
3. The combination of the piston-head I with the packing-case B, and rods C, substantially as herein shown and described.
4. The construction and arrangement of the bottom F, hinge G, and catch H, on the lower end of the packing-cylinder B, as herein set forth.

The above specification of my invention signed by me this fifteenth day of September, 1866.

F. A. L. CASSIDEY.
